UNITED STATES PATENT OFFICE

149,441

DESIGN FOR A STAPLE DRIVING MACHINE

Roy E. Peterson, Norwalk, Conn., assignor to The E. H. Hotchkiss Company, Norwalk, Conn., a corporation of Delaware

Application March 31, 1947, Serial No. 138,075

Term of patent 14 years

(Cl. D74—1)

To all whom it may concern:

Be it known that I, Roy E. Peterson, a citizen of the United States, residing at Norwalk, county of Fairfield, State of Connecticut, have invented a new, original, and ornamental Design for Staple Driving Machine, of which the following is a specification, reference being had to the accompanying drawing, forming part thereof.

The figure is a perspective view of a staple driving machine showing my new design, the opposite end being plain and the opposite side presenting substantially the same appearance as the side shown.

I claim:

The ornamental design for a staple driving machine, substantially as shown and described.

ROY E. PETERSON.
